UNITED STATES PATENT OFFICE.

JOHN E. MITCHELL AND ORVILLE MITCHELL, OF ST. LOUIS, MISSOURI.

COMBINED COTTON RECLEANER AND GIN.

Application filed December 30, 1927. Serial No. 243,690.

This invention relates to gins of the huller breast type, and has for its general object the provision of novel means operating within the breast of the gin for separating hulls and trash from the seed cotton before it is carried by the gin saws into the roll-box.

In an application of John E. Mitchell, one of the joint inventors herein, Ser. No. 211,317, filed August 8th, 1927, cleaning members are shown co-operating with hulling ribs and with that portion of the gin saws projecting between the hulling ribs into the breast of the gin, and while that invention is effective in cleaning the cotton, some difficulty is encountered in its use by reason of the fact that the hulling ribs themselves become clogged at or near the point where the seed cotton is carried by the gin saws through the spaces between the ribs and into the roll-box. In subsequent inventions of the said John E. Mitchell, rotating means were provided for cleaning the hulling ribs at the point referred to, and such means have efficiently served the purpose except under unusual conditions, such as where the cotton contains too much moisture, and in such cases, considerable difficulty is encountered in getting sufficient cotton through the spaces between the hulling ribs to properly supply the ginning roll in the roll-box. A rotating means for cleaning the hulling ribs of the character referred to is illustrated in an application of the said Mitchell filed November 25th, 1927, Ser. No. 235,602. The present invention is designed to prevent the seed cotton from hanging or clogging while being carried by the gin saws out of the breast of the gin into the roll-box and is characterized in this regard by the fact that the upper portion of the hulling ribs, providing spaces through which the seed cotton is carried from the breast into the roll-box, is eliminated, and ribs are provided having free ends terminating within the spaces between the gin saws outside of the roll-box so that the teeth of the gin saws, as the latter are rotated, pass beyond the free ends of these ribs and move for some distance in the clear before entering the roll-box.

The invention is further characterized by the provision of a cleaning roller rotating in the same direction as the gin saws and in proximity thereto, the point of closest approach of said cleaning roller to the gin saws

being substantially at the line of termination 55 of the free ends of said ribs.

Another feature of the invention consists in adjustably mounting the series of ribs, as a whole, so that their free ends can be moved toward or from the cleaning roller to vary the 60 intensity of the action of the latter on the cotton.

Another important feature of the invention is the provision of a hull roller located at the bottom of the breast of the gin and 65 also rotating in the same direction as the gin saws, which defines the size of a space for the discharge of hulls and trash from the breast of the gin, and is adjustable to vary the size of said space. This roller also func- 70 tions to throw cotton onto the gin saws.

Finally, we provide a feed roller which receives the cotton fed into the breast of the gin and delivers the same to the hull roller which latter, as stated, throws the same 75 onto the surface of the gin saws.

In the drawings:

Figure 1 is a longitudinal sectional view through a gin constructed according to our invention, the rear portion of the gin being 80 broken away;

Figure 2 is a view in side elevation on an enlarged scale of a portion of the gin illustrating the manner of adjusting the ribs which co-operate with the gin saws, and also the 85 manner of adjusting the hull roller; and

Figure 3 is a broken sectional view looking at the front or working side of the gin saw cylinder, further illustrating the means for adjusting the ribs. 90

Referring now to the drawing, the numeral 1 indicates the casing of a gin, in which casing is provided a roll-box 2 and a breast 3 formed by one wall 4 of the roll-box and the front wall 5 of the casing. A seed gate 5^a of the usual construction is provided at the lower end of the wall 4 of the roll-box. Depending from the rear side of the roll-box is a series of ginning ribs 6 which, as usual, pass through spaces between the gin saws 7 and have their sides located sufficiently close to the sides of the gin saws to prevent seeds from passing through the spaces between the ginning ribs. The series of gin saws 7, suitably spaced apart and mounted on a shaft 8, constitutes a gin saw cylinder. The numeral 9 indicates a doffer for removing lint from the gin saw cylinder. 100 105

In the ordinary double-rib gin, a second series of ribs similar to the ribs 6 and known as hulling ribs, is provided, which are located nearer the periphery of the gin saws but which provide spaces of sufficient width to permit the seeds to pass through them into the roll-box. The upper ends of these hulling ribs are fixedly secured to the lower end of the front wall 4 of the roll-box. As we have above pointed out, this arrangement is objectionable on account of the frequent clogging of the hulling ribs at the point where the gin saws pass between the same to enter the roll-box.

To overcome the disadvantage resulting from clogging of the hulling ribs, we provide ribs or guards 10 answering, generally, in purpose to that of the hulling ribs of prior constructions, but differing therefrom in that their upper ends 11 terminate below the roll-box within the spaces between the gin saws so that the disks of the gin saws move away from the ends of these ribs and travel for some distance in the clear before entering the roll-box.

Co-operating with the ribs 10 and gin saws 7 is a cleaning roller 12 mounted to rotate in the same direction as the gin saws and in proximity thereto, so as to continuously knock back any hulls or trash which may be carried up with the cotton engaged by the teeth of the gin saws. The point of closest approach of the cleaning roller 12 to the gin saws is substantially at the line of termination of the upper free ends 11 of the ribs 10. These ribs are secured at their lower ends to a cross-bar 13 which is pivotally mounted by means of a rod 14 in opposite sides of the gin. Secured at each end of the cross-bar 13, is an arm 15 of substantially the same shape and size as the ribs 10, one of said arms being shown in Fig. 3 and in dotted lines in Fig. 2. Each of these arms has a lateral projecting member 16 extending through an elongated opening 17 in the side wall 18 of the gin, the member 16 having in its outer end a screwthreaded aperture receiving an adjusting screw 19 rotatably mounted in a small bracket 20 on the side of the gin. Binding nuts 21 are mounted on the screw to engage, respectively, the bracket 20 and the outer side of the projecting member 16. By loosening these nuts and turning the screw 19 in one direction or the other, the cross-bar 13 may be turned on its pivot 14 to move the ends 11 of the ribs 10 closer to or further from the cleaning roller 12 to vary the intensity of the action of the cleaning roller on the cotton.

Rotatably mounted by means of a shaft 22 in the lower part of the breast 3 is a hull roller 23, which defines the size of a passage 24 past the gin saw cylinder for the escape of loose hulls and trash fed into the machine or similar particles knocked back from

the cotton by the cleaning roller 12. The roller 23 is adjustable toward and from the gin saw cylinder to vary the size of the passage 24 and this is preferably accomplished in the following manner:

Each end of the shaft 22 passes through a relatively large circular opening 25 provided in the corresponding side wall of the gin and is rotatably mounted in a circular plate 26 which is larger in diameter than the opening 25 and operates to cover and close the same. This plate is provided near opposite sides with corresponding slots 27 which fit over screwthreaded projections 28 mounted on each side of the gin. The plate is secured in position by means of nuts 29 screwed on these projections. By loosening the nuts 29 and moving the plate 26 in one direction or the other, the shaft 22 with its roller may be adjusted toward or from the gin saw cylinder, after which the nuts 29 are screwed tight to hold the plates in their adjusted positions.

Mounted in the breast 3 of the gin to one side (the left, as shown in Fig. 1) and slightly above the hull roller 23 is a feed roller 30, which preferably rotates in an opposite direction to that of the hull roller 23 and operates to deliver the uncleared or partially cleaned cotton fed into the breast of the gin onto the hull roller 23 which, in turn, throws it onto the surface of the gin saws 7. To avoid accumulation of material in the passage 24 below the gin saws, which might occur to some extent if the roller 23 were perfectly smooth, we prefer to provide the surface of the roller with projections, and these we have shown in the form of screws 31 which are screwed into the roller with their heads projecting beyond the surface thereof. These screws may be variously arranged on the surface, preferably in staggered relation, so that in rotating, the effective distance between the screws would be, say, one inch. These or similar projections will operate to positively remove and discharge from the breast any accumulation of trash which may form between the roller and the ribs 10 below the gin saws. The cleaning roller 12 and the ribs or guards 10 provide a space 32 between them, which extends the full length of the gin saw cylinder, and the adjustment of the upper ends of the ribs 10 above described operates to widen or narrow this space, with the object of varying the severity of the cleaning action of the roller 12 while the seed cotton is being carried through this gap into the roll-box. The provision of this space 32, the fact that the spaces between the ribs 10 are open at their upper ends, and the further fact that the ribs 10 terminate short of the roll-box, render it possible for two or more gin saws to engage the same lock of cotton and to carry it through the space 32 from the breast of the gin and into the roll-box without breaking the lint.

In the case of the ordinary hulling ribs, it is necessary for the saws to force the seed cotton through spaces between the hulling ribs, and a certain amount of machining or 5 breaking of the fibres takes place by reason of two or more saws engaging the same lock of cotton, each carrying a portion of it through different spaces between the ribs, and a portion of the fibres torn loose from 10 those carried through by the saws lodge on the ribs, causing them to clog up in the manner already referred to.

In the case of our invention, it will be seen that such an action as last described is impossible because the teeth of the saws never 15 pass between the ribs 10 and, therefore, no obstruction to the movement of the cotton carried by the teeth of the saws is presented. At the same time, the cleaning roller will 20 operate to knock back any pieces of hulls and trash adhering to the cotton, and the intensity of this action may be regulated by adjusting the ends of the ribs 10 toward or from the cleaning cylinder in the manner 25 previously described.

The numeral 33 indicates a pivoted gate or door which may be swung open to give access to the interior of the breast of the gin. Preferably at the upper end of this gate we 30 provide an angle bar 34 which acts in conjunction with the feed roller 30 as a breaker to crush any bolls which may be fed into the gin.

In the ordinary plain gin, that is, where no 35 provision is made for cleaning the cotton before it enters the roll-box, the seed cotton is fed directly into the roll-box through the top thereof. In the huller breast type of gin here illustrated, the cotton is fed into the breast of 40 the gin and hence enters the roll-box through the bottom thereof past the seed gate. The seed gate 5^a, therefore, may be considered as defining, roughly the bottom of the roll-box. As the seed cotton accumulates in the 45 roll-box, it is caused to rotate and the seeds, freed from the lint, fall out of the roll-box past the end of the seed gate and at points beyond the seed gate and slide down the ginning ribs 6 in the spaces between the saws 50 and out of the machine. It is a necessity of the operation of such a gin, therefore, that the path for the seeds out of the roll-box shall be unobstructed.

This provision for the free escape of the 55 seeds from the roll-box past the seed gate is retained in our construction in that, in the preferred embodiment thereof as shown in the drawing, the ribs 10 terminate below the roll-box or, more specifically, below the seed 60 gate 5^a. Thus, seeds escaping from the roll-box at or beyond the end of the seed gate, or even through the bars of the seed gate, as sometimes happens, will pass over the free 65 ends of the ribs 10 and fall past or over the ginning ribs 6 in the usual manner.

The upper ends of the ribs 10 could terminate at a point somewhat higher than that shown without departing from the spirit of our invention, the only limitation in this regard being that the ends of the ribs shall 70 offer no obstruction to the free passage over them of the seeds escaping from the roll-box.

In operation, seed cotton is fed into the breast 3 of the gin and falls directly onto the feed roller 30, which delivers it from its underside onto the hull roller 23, which in turn, throws it onto the gin saws 7 on the portion thereof projecting into the breast through the spaces between the ribs 10. The cotton is, of course, engaged and carried up by the gin 80 saws 7 and any hulls and trash are knocked back by the cleaning roller 12. The hulls and trash are discharged through the passage 24 and any loose locks of cotton thrown off by the cleaning roller 12, together, of course, 85 with the cotton being fed into the breast of the gin, is again thrown by the roller 23 onto the gin saws. The action of the gin saws on the seed cotton within the roll-box 2 is not described as it may proceed in the ordinary manner, so far as the present invention 90 is concerned.

We claim:

1. In a cotton gin providing a roll-box, cleaning mechanism located in the breast of the gin comprising, in combination with the gin saws, ribs secured at their lower ends and extending between the saws and having upper free ends terminating below the entrance from the breast of the gin into the roll-box, 100 there being an unobstructed space from the ends of said ribs into said roll-box traversed by the gin saws, and a cleaning roller rotating in the same direction as the gin saws and in proximity thereto.

2. In a cotton gin providing a roll-box, cleaning mechanism located in the breast of the gin comprising, in combination with the gin saws, ribs secured at their lower ends and extending between the saws and having upper free ends terminating below the entrance from the breast of the gin into the roll-box, 110 there being an unobstructed space from the ends of said ribs into said roll-box traversed by the gin saws, and a cleaning roller rotating in the same direction as the gin saws and in proximity thereto and to the free ends of said ribs.

3. In a cotton gin providing a roll-box, cleaning mechanism located in the breast of the gin comprising, in combination with the gin saws, ribs secured at their lower ends and extending between the saws and having upper free ends terminating in the spaces between the saws at a point below the entrance from the breast of the gin into said roll-box, 120 there being an unobstructed space from the ends of said ribs into said roll-box traversed by the gin saws, the disks of the gin saws, 125 in rotating, passing out of the spaces be- 130

tween the ribs at their open ends, and a cleaning roller rotating in the same direction as the gin saws and in proximity thereto and to the free ends of said ribs.

5. In a cotton gin providing a roll-box, cleaning mechanism located in the breast of the gin comprising, in combination with the gin saws, ribs secured at their lower ends and extending between the saws and having upper free ends terminating in the spaces between the saws below the roll-box, there being an unobstructed space from the ends of said ribs into said roll-box traversed by the gin saws, a cleaning roller rotating in the same direction as the gin saws and in proximity thereto at substantially the line of termination of the free ends of said ribs, and means for simultaneously adjusting the upper ends of all of said ribs toward or from said cleaning roller.

6. In a cotton gin providing a roll-box, cleaning mechanism located in the breast of the gin comprising, in combination with the gin saws, a cleaning roller rotating in proximity thereto and in the same direction, and ribs secured at their lower ends and extending between the saws and having upper free ends terminating in the spaces between the saws below the point of entrance to the roll-box and substantially at the point of closest approach of the cleaning roller to said gin saws, there being an unobstructed space from the ends of said ribs into said roll-box traversed by the gin saws.

35. 6. In a cotton gin providing a roll-box, cleaning mechanism located in the breast of the gin comprising, in combination with the gin saws, ribs secured at their lower ends and extending between the saws and having their upper free ends terminating in the spaces between the saws at a point below the entrance to the roll-box, there being an unobstructed space from the ends of said ribs into said roll-box traversed by the gin saws, and a cleaning roller rotating in the same direction as the gin saws and in proximity thereto and to the free ends of said ribs.

7. In a cotton gin providing a roll-box, cleaning mechanism located in the breast of the gin comprising, in combination with the gin saws, ribs secured at their lower ends and extending between the saws and having their upper free ends terminating in the spaces between the saws and below the entrance from the breast of the gin into the roll-box, there being an unobstructed space from the

ends of said ribs into said roll-box traversed by the gin saws, whereby seeds escaping from the roll-box may pass over the ends of said ribs in their passage out of the machine, and 60 a cleaning roller rotating in the same direction as the gin saws and in proximity thereto and to the free ends of said ribs.

8. In a cotton gin, cleaning mechanism located in the breast of the gin comprising, in 65 combination with the gin saws, ribs secured at their lower ends and extending between the saws and having upper free ends terminating in the breast of the gin in the spaces between the saws, a cleaning roller rotating 70 in the same direction as the gin saws and in proximity thereto and to the upper end portions of said ribs, and a hull roller located below said cleaning roller and rotating in the direction of the gin saws, said roller, on 75 its side nearest the gin saws, defining the size of a passage past the latter for the free escape of hulls and trash from the breast of the gin.

9. In a cotton gin, cleaning mechanism located in the breast of the gin comprising, in 80 combination with the gin saws, ribs secured at their lower ends and extending between the saws and having upper free ends terminating in the spaces between the saws, a cleaning roller rotating in the same direction as 85 the gin saws and in proximity thereto and to the free ends of said ribs, a hull roller located below said cleaning roller and rotating in the direction of the gin saws, said roller, on its side nearest the gin saws, defining the 90 size of a passage past the latter for the free escape of hulls and trash from the breast of the gin, and means for adjusting said hull roller toward and from the gin saws.

10. In a cotton gin, cleaning mechanism 95 located in the breast of the gin comprising ribs secured at their lower ends and extending between the saws and having upper free ends terminating in the spaces between the saws, a cleaning roller rotating in the same 100 direction as the gin saws and in proximity thereto and to the free ends of said ribs, a hull roller located below said cleaning roller and rotating in the same direction as said 105 gin saws and in spaced relation thereto, and a feed roller positioned to deliver seed cotton fed into the breast of the gin onto said hull roller.

In testimony whereof, we have hereunto set our hands.

JOHN E. MITCHELL.
ORVILLE MITCHELL.
